UNITED STATES PATENT OFFICE.

DANIEL KOPS, OF NEW YORK, N. Y., ASSIGNOR TO KOPS BROS. INC., OF NEW YORK, N. Y., A CORPORATION OF NEW YORK.

APPAREL CORSET.

Application filed May 8, 1923. Serial No. 637,408.

To all whom it may concern:

Be it known that I, DANIEL Kops, a citizen of the United States, residing in the borough of Manhattan, city, county, and 5 State of New York, have invented an Improvement in Apparel Corsets, of which the following is a specification.

My present invention relates to an apparel corset and more particularly to the 10 construction of a closed back garment. The construction of the front of the garment may be of any desired type, for example, as is shown in Letters Patent No. 1,432,470, granted to me October 17, 1922. In this and 15 other forms of closed back corset garments as heretofore constructed due to the manner in which the lower portion of the garment is made and the tension applied thereto in the adjustment of the garment to the body of the 20 wearer it has been difficult to prevent the stays at the upper portion of the back from extending outwardly particularly when the wearer is in a seated position. This tendency of the stays to extend outwardly at 25 the upper central portions of the back, it being understood, is due largely to the tendency of the pressure exerted on the garment to cause the lower end of the stays to conform closely to the body at the lower ends 30 thereof thereby tending to force the stays outwardly at their upper ends particularly when the garment is so constructed as to permit of any play circumferentially in the upper portions thereof.

35 The object of my present invention is to overcome this difficulty and in so doing the garment in which the invention is incorporated is made with a portion of the back section provided with stays and having the 40 upper edge thereof appreciably distant, that is lower than the upper edge of the garment and fitted with a strap which at its upper edge completes the continuity of the garment and overlies the upper portion of the 45 said back section so as to extend over the same and the upper ends of the stays therein so as to exert a tension thereon to prevent these stays and the upper portion of the back section from extending outwardly from 50 the body particularly when the wearer of the garment is in a seated position, as will be hereinafter more particularly described.

In the drawing:

Fig. 1 is a perspective view illustrating an

apparel corset made in accordance with this 55 invention.

Fig. 2 is an elevation on an enlarged scale illustrating a portion of the upper back members of the garment, this figure showing the inner side of the garment. 60

Fig. 3 is also an elevation of the back of the garment on an enlarged scale showing the outer side thereof, and

Fig. 4 is a section on line 4—4, Fig. 2.

As hereinbefore stated the construction of 65 the front of the garment in which my present invention may be incorporated is preferably similar to that shown and described in Letters Patent No. 1,432,470, granted to me October 17, 1922. It will be understood, 70 however, that this or any other desirable front construction may be employed. The invention in this case relates more particularly to the construction of the upper portion of the garment at the back thereof. By 75 reference to the drawing it will be seen that in carrying out the invention I employ as is usual the body member of the garment in which there is in each portion thereof side sections indicated at 10. The back of the 80 garment preferably includes a relatively narrow back central section 11 and intermediate back sections 12 and 13 adjacent thereto, together with distant back sections 14 and 15 85 adjacent and suitably secured to the back sections 12 and 13 respectively. The central back section 11 is preferably continuous to the lower edge of the garment, while the back sections 12 and 13 adjacent thereto terminate at their lower edges along a line 90 appreciably above the lower edge portion of the body of the garment and the lower edges of the back sections 14 and 15 are continuations of the lower edges of the back sections 12 and 13 respectively. The back section 12 95 is preferably fitted with suitable stays indicated at 16 and 17, and similarly the back section 13 is fitted with stays indicated at 18 and 19. The stays 16 and 18 are placed adjacent the edges of the central back section 11 and extend from the upper edge thereof to approximately the lower edges of the garment, while the stays 17 and 19 are suitably spaced from the stays 16 and 18 and extend approximately from the upper 105 to the lower edges of these back sections in which they are placed. I also employ suitable stays indicated at 20 in this portion of

the garment at which the back sections 12 and 14 are connected, and also similar stays 21 in that portion of the garment in which the back sections 13 and 15 are connected. 5 These stays 20 and 21 extend from the upper edge of the garment to the lower edges of the back sections 12 and 13 respectively.

As will plainly appear from the drawing the upper edges of the central back section 10 and the back sections 12 and 13 adjacent thereto as indicated at 22 are substantially in the same line which is appreciably lower than the upper edge of the garment, while the upper edges of the back members 14 and 15 are continuations of the upper edge of the garment so that in the body of the garment at the upper edge thereof in a centrally disposed position there is a cut away portion defined at its ends by the lines 23 and 24 and circumferentially of the garment by the upper edges of the back sections 11, 12 and 13. 20

I also employ a back tension strap member 25. This is connected in the garment at the opposite ends thereof substantially along the lines indicated at 26, 27 respectively and by which the adjoining edges of the back sections 12 and 14 and the back sections 13 and 15 are connected, the strap 25 further 30 more being so placed in the garment that the upper edge thereof forms a substantial continuation of the upper edge of the garment or in other words the upper edge of this strap completes the continuity of the upper edge of the garment at the central back portion thereof. This tension strap 25 in its normal condition is slightly shorter than the upper edge of the back sections 11, 12 and 13 so as to permit the strap to stretch 40 when tension is applied to the garment to extend the upper portions of these back sections. The strap 25 as clearly indicated in the drawing extends below the upper edges of the back sections 11, 12 and 13 so as to cover an appreciable portion of the same 45 at the upper ends thereof. The lower edge of this back tension strap which is preferably made of elastic webbing is indicated at 28, while the lower edges of the back sections 12 and 14 and the lower edges of the back sections 13 and 15 are indicated at 29 and 30 respectively.

In the lower central portions of the garment at the back of the same I preferably 55 employ tension straps 31 and 32 which are similarly placed on the opposite sides of the back central member 11. The lower edges of these tension straps 31 and 32 complete the continuity of the lower edge of the garment and the straps extend upwardly so as to overlie the lower portions of the back sections 12 and 14 and the back sections 13 and 15 an appreciable distance as is clearly indicated in Fig. 3, the upper edges of these lower tension straps being indicated at 33

and 34 respectively. These lower tension straps 31 and 32 extend from the central section 11 at the back of the garment to the side sections 10 thereof and the corresponding edges of these tension straps are suitably connected respectively to the said back central section 11 and the corresponding side section 10. These lower tension straps 31 and 32, however, form no part of the present invention. 75

It will now be apparent that in the use of the garment the tension strap 25 which is on the outer portion of the garment will cause the upper portions of the back sections of the corset to lie closely against the body of the wearer so as to prevent the same from extending outwardly which otherwise would be the case particularly when the wearer of the garment is in a seated position. 80

I claim as my invention:

1. In an apparel corset, a back section having its upper edge appreciably below the upper edge of the corset, a plurality of stays having their upper ends adjacent the upper edge of the said back section and extending downwardly therefrom, and a tension strap, the upper edge of which completes the continuity of the upper edge of the corset at the back thereof and which overlies the upper portion of the back section and the upper ends of the said stays to prevent the upper end of the back section from extending outwardly when the wearer of the garment is in a seated position. 95

2. In an apparel corset, a relatively narrow back central section, back sections adjacent the said central back section, the said back sections being connected and having their upper edges appreciably below the upper edge of the corset, stay members in the said back sections, each stay member having its upper end adjacent the upper edge of the back section in which it is placed and extending downwardly therein, and a tension device extending across the back sections with its upper edge completing the continuity of the upper edge of the corset and its lower portion overlying the upper ends of the said back sections and the stays therein to prevent the upper portions of the back sections from extending outwardly when the wearer of the garment is in a seated position. 105

3. In an apparel corset, a central back section, back sections distant from the central back section, back sections intermediate of the said central and distant back sections, the upper edges of the said distant back sections being continuations of the upper edges of the corset, while the upper edges of the central and intermediate back sections are appreciably below the upper edges of the corset and the distant back sections, a plurality of stays in the said back sections, each stay having its upper end 110

- adjacent the upper edge of the back section in which it is placed and extending downwardly therein, and a tension strap secured at its ends to the upper portions of the said distant back sections so as to overlie a portion of the upper ends of the said central and intermediate back sections and the upper ends of the stays therein, while the upper edge of the said tension strap 10 completes the continuity of the upper edge of the corset so as to prevent the upper ends of the central and intermediate back sections from extending outwardly when the wearer of the corset is in a seated position.
- 15 4. In an apparel corset, a central back section, back sections distant from the central back section, back sections intermediate of the said central and distant back sections, the upper edges of the distant back sections being continuations of the upper edge of the garment, while the upper edges of the central and intermediate back sections are appreciably below the upper edge of the garment, stays placed on opposite sides of the central back section and extending 25 from the upper ends of the central and intermediate back sections to substantially the lower edge of the garment, stays placed in the said intermediate back sections and extending substantially from the upper to 30 the lower edges thereof, and other stays extending from substantially the upper edge of the distant back section to the lower edge thereof, the lower edges of the said intermediate and distant back sections being continuations of each other, and an elastic tension strap secured at its ends to the upper portions of the said distant back sections so as to overlie a portion of the upper ends of the said central and intermediate back 35 sections and at its upper edge substantially completing the continuity of the upper edge of the garment so as to prevent the upper ends of the central and intermediate back sections from extending outwardly from the 40 body when the wearer is in a seated position.
- 20

Signed by me this 19th day of April, 1923.
DANIEL KOPS.
